UNITED STATES PATENT OFFICE.

PHILIPPE DE CLAMECY, OF BOSTON, MASSACHUSETTS, ASSIGNOR TO CORONA TYPE-WRITER COMPANY, INC., A CORPORATION OF NEW YORK.

TYPE-WRITING MACHINE.

1,278,875.

Specification of Letters Patent. Patented Sept. 17, 1918.

Application filed March 6, 1916. Serial No. 82,404.

To all whom it may concern:

Be it known that I, PHILIPPE DE CLAMECY, a citizen of the United States, and a resident of Boston, county of Suffolk, and State of 5 Massachusetts, have invented certain new and useful Improvements in Type-Writing Machines, (Case F,) of which the following is a full, clear, and exact description.

This invention relates more particularly 10 to the case shift mechanism of a front strike or other visible typewriting machine which may be made compact when not in use to adapt the same for transportation and other purposes.

15 One of the principal objects of the invention is to provide a small compact portable typewriter in which the keyboard, including the shift keys, is mounted upon a frame part of the main frame and is slidably held to a 20 main frame part, and is movable with the shift keys from a normal operative or extended position to an abnormal and more compact one when not in use, and at the same time, if desired, so to construct the 25 frame that it may form an inclosing case for not only the typewriter mechanism but also the keyboard including the shift keys.

Another object of the invention is to provide a writing machine wherein the platen 30 carriage may be given a shift movement, and said carriage given an additional abnormal movement to place the platen in an operative and more compact position with respect to the type.

35 Other objects of the invention are to provide simple and efficient shift mechanism whereby the platen and carriage may be moved from a normal operative position for lower case writing to relatively different distances to adapt type-bars to have a plurality of type thereon; and to provide a case shift mechanism wherein shift keys may be moved relatively to other parts of the typewriter from a normal operative position to 40 a more compact one and the connection between the shift keys and the parts operated thereby maintained without any disconnection or separation.

A further object of the invention is to 45 provide a typewriter in which the case shift mechanism includes a flexible and collapsible connection to adapt relative movements between the parts thereof.

With these and other objects in view, the 50 invention will be hereinafter more particu-

larly described with reference to the accompanying drawings, which form a part of this application, and will then be pointed out in the claims at the end of the description:

In the drawings, Figure 1 is a longitudinal 55 section, partly in elevation, of one form of machine embodying the invention.

Fig. 2 is a fragmentary sectional plan taken on the line II—II of Fig. 1, showing means whereby the mounting for the shift 65 keys may be held in a normal operative or in a compact position.

Fig. 3 is a vertical section taken on the line III—III of Fig. 1.

Fig. 4 is a vertical transverse section taken 70 on the line IV—IV of Fig. 5.

Fig. 5 is a sectional plan view, partly in elevation, showing the case shift mechanism and other parts of the machine.

Fig. 6 is a longitudinal section, partly in 75 elevation, similar to Fig. 1, except that the parts have been moved to a compact position.

Fig. 7 is a vertical section of one side of the machine taken on the line VII—VII 80 of Fig. 6; and

Fig. 8 is an enlarged fragmentary vertical section taken on the line VIII—VIII of Fig. 1.

While the invention is shown as applied 85 to a particular kind of typewriter in which the keyboard is mounted and connected to the type-bars in a particular way and the different mechanisms are shown of a particular construction, it will be understood that 90 many of these parts may be changed, and that some of the parts may be dispensed with or others substituted therefor without changing the nature or character of the invention.

The inclosing case 10 or other frame or support for the different parts of the typewriter may be variously constructed. As shown, the case or frame 10 comprises a main substantially box-like frame part 11, 100 having a base 11^a, a rear wall 12 a partially open front wall 12^a and side walls 13. The base 11^a may be continuous or may have two offset parts 13^a and 14, as shown in the drawings, said offset parts being provided with 105 the usual supporting rubber feet 15, if desired. A top or cover member 16, is hinged at 17 to the upper part of the rear wall 12, and at the end opposite the hinge 17 of said cover member or top 16 is a front plate or 110

member 18. This member 18 is hinged at the forward edge of the top 16, and is adapted to inclose the open front or space 19 of the main part, member or section 11. At the 5 front portion of the main frame part is a keyboard member or frame part 20. This frame part 20 is slidably held to move horizontally within the main member 11 from a normal operative and extended position, 10 as shown in Fig. 1, to an abnormal compact one, as shown in Fig. 5. The frame part of member 20 may have a substantially box-like form of considerably less height and length than the main frame part 11, and said 15 frame part has a base 21 on which may be supporting feet 22, a front wall 23 having an extended portion, as 24, by which the frame part 21 may be moved inwardly and outwardly and a top portion or plate 25. 20 The base 21 of the frame part 20 is adapted to slide forwardly and rearwardly on the offset base part 14 and has its side walls 26 provided with slots 27. These slots 27 are each adapted to be engaged by the shank 25 28 of a pin or bolt 29, and engaging the threaded end of the shank 29 of each bolt is a thumb nut 30. The shank of the bolt 28 has a square portion to fit the slot 27 and forms a bearing portion and guide for the 30 sides of the frame part 20 during its horizontal sliding movement. Each bolt has an enlarged head 31 so that by tightening the thumb nuts 30 at each side of the machine the extensible and slidable frame part 20 35 may be held either in its extended normal position or in its compact abnormal position. The front plate 18 of the inclosing case is adapted to rest against the upper surface of the top 25 of the frame part 20 when in 40 a compact condition, and mounted upon the part 18 is a lock 32, as for example a lock such as is employed on desks and which is accessible by a key through an opening or keyhole 33 whereby the tumblers of the lock 45 may be disengaged from or engage a slot 34 or other holding means in the top 25 of the frame part 20 to lock said frame part against access except by means of the key. The front part 18 may be also provided 50 with a handle, as 35, for carrying purposes, and at the rear portion the case may have end pieces, as 36, to adapt the platen carriage, as will be presently described, to have free movement transversely of the machine 55 when in use. The side or end pieces or members 36 are hinged to the rear wall 12 and are adapted to inclose the cutaway portions 37 of the side walls of the main frame part 11. The side pieces 36 have beaded or 60 rabbeted edges and the top member 16 may also be provided with a rabbeted or beaded edge so as to lock the end pieces or members 36 in a closed position when in the position shown in Figs. 1 and 7. 65 On the frame part 20 is mounted the key-board 38. The keyboard may be of the usual standard or universal kind wherein a plurality of banks or groups of keys are arranged each operating individual type, such banks being in three or more sets, according 70 to the number of printing characters, and whether or not a single case or double case shift is employed. The keys 39 are each arranged upon a vertically movable stem or rod 40. Each stem 40 is guided in a bushing 75 or tubular part 41 extending upwardly from the top 25 of the keyboard frame part 20, and at the lower end of each stem 40 is a yoke or head 42 to which is pivotally connected the arm 43 of a bell-crank lever 44. 80 The bell-crank lever 44 is pivoted at 45 to a lug or bracket 46 extending inwardly from the frame part 20, said part 46 extending inwardly from the top 25 for two banks or rows of key-operated levers and from the 85 front plate 23 of the frame part 20 for the third row of key-operated levers. The key-operated levers 44 have a pin-and-slot connection with the stems 40 and under each head 42 is a rubber or other strip 47 to take 90 the shock due to the return movement of the rods 40. The arms 48 of the key-operated bell-crank levers are connected to springs 49, there being a spring for each lever and each spring being connected at one 95 end to a part of the frame part 20 and at its other end to one of said levers. A link or connection 50 extends from each key-operated lever and has one end held to the short arm 51 of a lever 52. The links or connections 50 may be of wire, as piano wire, or of any other desired form, and is adapted when a key is depressed to force the upper arm 53 of one of the levers 52 inwardly. The levers 52 are all mounted on a common 100 pivot rod 54 which is curved according to the arrangement of the levers 53 and the parts actuated thereby. The arms 53 of each lever 52 is pivoted at 55 to a link 56, said link 56 being pivoted at 57 to a lug 58 of a 105 type block or head 59. Each type block has a plurality of characters or type 60 thereon, in this case three characters because there is double case shift, as will be presently described, one of said characters 110 representing the lower case type, another character the upper case type, and the third character or type, figures, punctuation marks, etc., this arrangement being varied according to the construction of the machine. The 115 type heads or blocks 59 are held to bars 61. Each bar 61 is guided to slide in a bearing 62 and is normally forced in one direction by a spring 63, one end of which is held to the forward end of said bar and the other end to a part of the main casing or frame. The bars 61 are held in slots and over the bars is a finishing and a retaining plate 64. The bars 61 are arranged in a curved path 120 so that as they are propelled or forced in- 125 130

wardly they will move toward the printing point to impress a character upon the work held upon the platen 65. The bars 61 are thus substantially radially arranged with respect to the printing point so that all the type of all the bars as each one is forced inwardly through the movement of the levers 52, links 56 and bars 61 on the depression of the keys 39 will strike at the same point 10 on the work sheet. This arrangement of the type-bars is not broadly new. Instead of the type-bars having a horizontal sliding movement they may have an upward and rearward movement as is common in most 15 standard visible writing machines.

The platen 65 is rotatably mounted upon end pieces or brackets 66 of a carriage 67. The platen carriage 67 has a base 68 which is constructed to move transversely of the 20 machine and may be guided in grooves in a carriage bed 69. The carriage bed 69 is held to move vertically at its ends for case shift as will be presently described. The platen carriage may have the usual parts mounted 25 thereon which coöperate with the platen, such as line-spacing, ribbon vibrating mechanism and other features usually employed in connection with typewriting machines. Some of the parts which are common to the 30 ordinary typewriter are not shown and some features are shown in part and others simply suggested. There may be one or more feed-rolls, only one being shown, as roll 70, and adapted to guide the paper or work- 35 sheet about the platen is a paper apron 71. Paper fingers 72 are held upon a transversely extending rod 72^a which may be graduated or not, as desired, and these paper fingers are adapted to be held in various po- 40 sitions by means of thumb-screws 72^b so that different widths of paper may be properly guided about the platen 65. The platen may be of usual construction and has its shaft 73 projecting beyond the end bracket 45 66, and on each end of said shaft may be a knob 73^a by which the platen may be rotated independently of its line-spacing mechanism in the usual way. The platen may have a ratchet wheel 74 at one end thereof 50 and adapted to engage the teeth of the ratchet wheel is pawl 75, the latter being pivotally held to a finger lever 76. The lever 76 and pawl 75 is adapted to rotate the platen in its bearings for line-spacing, and 55 while variable spacing is not provided for it will be evident that the construction may be such that the platen may be moved for single, double or variable spacing as is common in many types of writing machines.

60 The platen carriage is given a vertical movement for upper case printing, and in this particular machine the platen carriage has two shift movements to adapt the type heads each to have three characters thereon.

65 The normal operative position of the platen

with respect to the type on the blocks 59 is such that the printing point is directly in line with the lower type character on each type block, the normal position of the platen and carriage being obtained by mechanism 70 presently to be described. The carriage bed 69 is held to vertically movable parts or slides 77. These slides 77 have a dovetail connection, as 78, with the enlarged parts or guides 79 located on opposite sides of the main frame part 11, so that the carriage and platen may be moved vertically and uniformly guided at both ends during such vertical movement. A pin 80 extends inwardly from each part 77 of the platen carriage and adapted to engage said pins are arms 81 and 82. The arms 81 and 82 are arranged in sets, there being an arm of each set located at opposite sides of the machine to impart uniform vertical movement to the 85 platen carriage. The arms 81 and 82 are slotted to permit relative movement between the arms 81 and 82 and the carriage for the different shift movements of the platen carriage. The arms 81 are connected to bell- 90 crank levers 83 and the arms 82 to bell-crank levers 84. These levers 83 and 84 are arranged in sets, the levers 84 being held to a transversely extending rod 85 and the bell-crank levers 83 to a transversely ex- 95 tending rod 86 whereby the bell-crank levers on opposite sides of the machine may be moved in pairs, said rods 85 and 86 having bearings in lugs 86^a on the frame base part 13^a. The arms 87 of the bell-crank levers 100 83 and the arms 88 of the bell-crank levers 84 are of relatively different and of such lengths that the same movement of said arms are adapted to impart different shift movements to the platen carriage according 105 to the spacing between the type on the blocks or heads 59. The bell-crank levers 83 and 84 are each connected by a wire link 89 and these wire links are connected to key-operated bell-crank levers in the same 110 way as the links 50 are connected to the bell-crank levers 48. Two shift keys 90 and 91, Fig. 5, are located on one side of the machine, and these keys when depressed will operate the bell-crank levers 83 and 84 to 115 impart different shift movements to the platen carriage as already described.

The links 50 and 89 are guided in a transversely extending bar 92, there being an aperture in said bar for each link so that 120 the links are properly held spaced apart. The bar 92 is held to one end of links 93 and these links at their other ends are pivotally held at 94 to the sides of the frame part 20. The ends of the bar 92 are guided in slots 95 of arms 96. These arms 96 are located on opposite sides of the machine and are pivotally held at 97 to lugs 98 ex- 125 tending upwardly from part 14 of the main frame part 11. The upper ends of the arms 130

96 are pivoted to links or connecting rods 99 and these links 99 are pivoted at their inner ends to arms 100. The arms 100 are held to studs 101 and on said studs 101 are 5 eccentrics 102 so that as the links 99 are forced inward the arms or cranks 100 will rotate the eccentrics 102. In the compact position of the parts as shown in Fig. 6, the printing point of the platen is below 10 the plane of travel of the lower case type on the type heads or blocks. When the keyboard frame part 20 is moved outwardly to a normal operative position, the transverse bar 92 by reason of its connection with 15 the links 93 will force the arms 95 downwardly from the position shown in Fig. 6 to that shown in Fig. 1. This downward movement of the arms 96 will force the links 99 forwardly and such forward movement of said links 99 will rotate the eccentrics 20 and this will elevate the carriage and platen to its normal operative position 25 wherein the printing point of the platen is in a direct line with the travel or movement of the lower type character of the type-bars. In this position the platen may be shifted for the different type characters as 30 already described, and may be restored to its normal position on the release of the shift keys either by gravity or by spring or springs, not shown, for that purpose. During the compact movement when the keyboard frame 20 is moved inwardly within the case such movement will elevate the 35 bar 92 by reason of the link connection 93, and this will raise the arms 96 and force the links or arms 99 inwardly thereby rotating the eccentrics 102 which will permit 40 an abnormal movement of the carriage and platen allowing the same to drop below the path of the type to an inoperative position. During this compact movement the wire link connections are raised by the bar 92 and are maintained in their proper relation 45 by reason of said bar 92 and without liability of becoming entangled. A connection is thus always maintained between the key-operated levers and the type-bars as well as between the shift keys and the parts 50 operated thereby, and during the extended and compact movement of the keyboard the normal and abnormal position of the platen and carriage is automatically effected through the action of the eccentrics 102 and 55 the connection between said eccentrics and the keyboard frame part 20 as already described.

In the drawings I have illustrated a form 60 of escapement mechanism for controlling the letter-feed movement of the carriage, ribbon mechanism, and other features of a complete typewriting machine; but these features form no part of the present invention, and for that reason it was thought unnecessary to describe the same in detail as

they form parts of separate applications filed by me March 6, 1916, Serial No. 82,403 and Serial No. 82,406.

Having thus described my invention, what I claim as new and desire to secure by Letters Patent, is:—

1. In a typewriting machine, the combination of a main frame part, a keyboard frame part slidably held to the main frame part to move from a normal operative position to a more compact one and within the main frame part, a platen carriage, supporting means for the platen carriage mounted in the main frame part, means for elevating the platen carriage and its support relatively different distances, and means operatively connected to the keyboard frame part for moving the platen carriage to a normal operative position or to permit said platen carriage to move to an abnormal and inoperative position 85 during the movement of the keyboard frame support.

2. In a typewriting machine, the combination of a main frame part, a keyboard frame part movably held to the main frame part to move from a normal operative position to a more compact one, a carriage, type-bars, supporting means for the carriage mounted in the main frame part, means for elevating the carriage to adapt the type-bars to have a plurality of type, and means operatively connected to the keyboard frame part for moving the carriage to a normal operative position or to permit said carriage to move to an abnormal and compact position during 100 the movement of the keyboard frame support.

3. In a typewriting machine, the combination of a main frame part, a keyboard frame part slidably held to the main frame part to move from a normal operative position to a more compact one, a platen carriage, supporting means for the platen carriage movable in the main frame part, means for elevating the platen carriage and its support relatively different distances, and means including links operatively connected to the keyboard frame part for permitting said platen carriage to move to an abnormal and compact position during the movement of 115 the keyboard frame support.

4. In a typewriting machine, the combination of a main frame part, a keyboard frame part slidably held to the main frame part to move from a normal operative position to a more compact one and within the main frame part, a platen carriage, supporting means for the platen carriage mounted in the main frame part, means for shifting the platen carriage, and means operatively connected to the keyboard frame part for automatically controlling the position of the platen carriage independently of its shift movement.

5. In a typewriting machine, the combi- 120

nation of a main frame part, a keyboard frame part slidably held to the main frame part, key-operated levers mounted on the keyboard frame part, a platen carriage,

5 means whereby the platen carriage may have a letter-space movement, levers operatively connected to the platen carriage to move the same relatively different distances, flexible connections between the key-operated levers and the shift levers, a guide bar for said flexible connections, and means whereby the guide bar may be elevated during the compact movement of the keyboard frame part and lowered during the outward movement

15 of said frame part.

6. In a typewriting machine, the combination of a main frame part, a keyboard frame part movably held to the main frame part, key-operated levers mounted on the key-

20 board frame part, a platen carriage, and means for shifting the platen carriage, including collapsible connections, adapted to be extended or collapsed during the movements of the keyboard frame part.

25 7. In a front-strike typewriting machine, the combination of a main frame part, a keyboard frame part slidably held to the main frame part, key-operated levers mounted on the keyboard frame part, a platen carriage, shift levers, flexible connections be-

30 tween the key-operated levers and the shift levers, a guide bar for said flexible connections, and means whereby the guide bar may be elevated during the compact movement 35 of the keyboard frame part and lowered during the outward movement of said frame part.

8. In a typewriting machine, the combination of a main frame part, a keyboard frame part movably held to the main frame part, a key-operated shift lever mounted on the keyboard frame part, a platen carriage, means including flexible connections between the key-operated shift lever and the platen 45 carriage to shift the latter, a guide bar for the flexible connection, and means whereby the guide bar may be elevated during the compact movement of the keyboard frame part and lowered during the outward movement

50 of said frame part.

9. In a typewriting machine, the combination of a main frame part, a keyboard frame part slidably held on said main frame part, key-operated levers forming a part of a universal keyboard mounted on said keyboard frame part, arms pivotally held to the main frame part, links operatively connected to said arms and to the keyboard frame part, means operated by said arms to move the 55 platen carriage from an abnormal compact position to a normal position, and means for shifting the platen carriage.

10. In a typewriting machine, the combination of a main frame part, a keyboard frame part movably held on said main frame

part, printing instrumentalities, case shift mechanism, arms pivotally held to the main frame part, links connected operatively to said arms and to the keyboard frame part, and means operated by said arms to move the 70 platen carriage from an abnormal compact position to a normal position.

11. In a typewriting machine, the combination of a support, a platen carriage, vertically movable means forming a support 75 for the platen carriage, eccentrics for moving the platen carriage from an abnormal position to a normal operative position, means for operating the eccentrics to permit the platen carriage to move to an abnormal 80 position, levers operatively connected to shift the support vertically different distances, and key-operated means for moving said levers.

12. In a typewriting machine, the combination of a main frame part, a keyboard frame part movably held to the main frame part, key-operated levers mounted on the keyboard frame part, a platen carriage, means for shifting the platen carriage, in- 90 cluding collapsible connections, and means for extending or collapsing said flexible connections during the movements of the keyboard frame part.

13. In a typewriting machine, the combination of a main frame part, a keyboard frame part relatively movable thereto, type bars having a plurality of characters thereon, means for shifting the platen carriage including key-operated levers mounted on 100 the keyboard frame part, and means whereby the platen carriage may be moved vertically to an abnormal compact position independent of the shift movement.

14. In a collapsible typewriting machine, 105 the combination of a main frame having parts adapted to be moved relatively to each other to collapse the machine, a platen support, case shift means for shifting said support, and mechanism actuated by collapsing 110 and extending the main frame parts for moving the platen support vertically to and from an abnormal compact position.

15. In a typewriting machine, the combination of a main frame part, a keyboard frame part slidably held to the main frame part to move from a normal operative position to a more compact one and within the main frame part, a platen carriage, supporting means for the platen carriage 120 mounted in the main frame part, means for shifting the platen carriage, and means operatively connected to the keyboard frame part for automatically controlling the vertical position of the platen carriage independently of its shift movement.

16. In a typewriting machine, the combination of a main frame part, a keyboard frame part movably held to the main frame part, a key-operated shift lever mounted on 130

the keyboard frame part, a platen carriage, means including flexible connections between the key-operated shift lever and the platen carriage to shift the latter, a guide bar for 5 the flexible connection, and means whereby the guide bar may be moved to collapse the flexible connection during the compact movement of the keyboard frame part, and extended during the outward movement of 10 said frame part.

17. In a typewriting machine, the combination of a main frame part, a keyboard frame part movably held on the said main frame part, a platen carriage, case shift 15 means therefor, eccentrics for moving the platen carriage from an abnormal compact position to a normal operative position, and means connecting said eccentrics to the keyboard frame part and adapted to move said 20 eccentrics when said keyboard frame part is moved relatively to the main frame part.

18. In a typewriting machine, the combination of a main frame part, a platen carriage, a support for the platen carriage mounted within the main frame part, means 25 for vertically moving said platen carriage support within the main frame part to place the platen in an elevated operative position and in a lowered inoperative compact position 30 within the main frame part, and case shift mechanism for imparting to the platen support vertical movement in addition to its compacting and extending movements.

19. In a visible typewriting machine, the combination of a casing having a substantially 35 box-like main frame part and a substantially box-like keyboard frame part slidably held to move relatively to each other from a normal operative extended position 40 to a more compact one, means whereby the said main frame parts may form a part of an inclosing case, a platen carriage adapted to move transversely of the machine and having three operative positions and an abnormal and inoperative and compact one, type, 45 and keys mounted on the keyboard frame part and operatively connected to move the type.

20. In a typewriting machine, the combination of a main frame part, a platen carriage movable transversely of said main frame part, supporting means for the platen carriage, case-shift means for moving the supporting means and carriage, a movable 55 keyboard frame part, key-operated levers mounted on said keyboard frame part and forming a part of a universal keyboard, a transversely extending bar, type-bars, levers operatively connected to the type-bars, there 60 being a lever for each type bar, a flexible connection between the key-operated levers on the keyboard frame part and the levers for operating the type bars, said transversely extending bar having a plurality of 65 apertures, one for each type bar lever, said

apertures being adapted to form a guide for each flexible connection, arms pivotally held to the main frame part in which the transversely extending bar is guided, a connection between the keyboard frame part and the transversely extending bar to cause said bar to be raised or lowered according to the direction of movement of the keyboard frame part, and means operated by the pivotally held arms adapted to move the 70 platen carriage and its support to a normal position when the keyboard frame part is moved in one direction and permit the platen carriage and its support to move to an abnormal inoperative position when the keyboard frame part is moved in the opposite direction. 75

21. In a visible typewriting machine, the combination of a main frame part and a keyboard frame part movable relatively to each other from a normal operative extended position to a more compact one, type mounted on the main frame part, a platen mounted on the main frame part to have a plurality of operative positions and an abnormal inoperative and compact position relatively to the type, and keys mounted on the keyboard frame part and having constantly maintained mechanical operating connections with the type. 80

22. In a typewriting machine, the combination of type bars, a keyboard having keys operatively connected at all times to the type bars and movable from a normal operative position to a more compact one, a platen carriage movable from a normal operative position to a more compact one, and means for shifting the platen carriage to adapt the type bars to have a plurality of type thereon. 90

23. In a typewriting machine, the combination of type bars, a universal keyboard provided with keys arranged in banks having a fixed relation to each other and operatively connected at all times to the type bars, said keyboard being slidably held to move as a whole from a normal operative position to a more compact one, a platen carriage movable from a normal operative position to a more compact one, and case shift means for shifting the platen carriage, said carriage and keyboard being always maintained in an upright position. 100

24. In a collapsible typewriting machine, the combination of a base frame part, type bars mounted on the base frame part, keys operatively connected to actuate the type bars, a vertically movable platen support, a platen carried by said support, co-operating relatively slidably means carried by said support and base frame part for guiding said support vertically and maintaining the same upright at all times, means for moving the platen support vertically from an abnormal inoperative compact position to an elevated position in co-operative relation to the type 110 115 120 125 130

- bars, and means for imparting a vertical case-shift movement to the platen support when said support is in its elevated operative position.
- 5 25. In a collapsible typewriting machine, the combination of a base frame part, type bars mounted on the base frame part, keys operatively connected to actuate the type bars, a platen support movable vertically 10 within the base frame part at the rear of the type bars, a platen carried by the support, coöperating relatively slidable means carried by the base frame and support adapted to maintain the support in an upright position at all times and to guide the support
- vertically, means for maintaining the support in an elevated position to support the platen in coöperative relation with the type bars, said means being operable to permit sliding of the support downwardly within 20 the base frame part at the rear of the type bars to an abnormal lower position to collapse the machine, and means for imparting a vertical case shift movement to the platen support when said support is in its normal 25 elevated position.

This specification signed this 2d day of March, A. D. 1916.
